BASKET STRUCTURE

Jerry Geralds, Detroit, Mich., assignor to Mid-West Wire Products Company, Inc., Detroit, Mich., a corporation of Michigan

Original application June 22, 1942, Serial No. 448,017. Divided and this application April 19, 1943, Serial No. 483,622

2 Claims. (Cl. 220—19)

1

This invention relates generally to basket structure such as wire baskets adapted to carry machine parts and the like, and constitutes a division of my application filed June 22, 1942, bearing Serial No. 448,017, now Patent No. 2,364,705 dated December 12, 1944.

Heretofore, sheet metal or pressed metal trays or the like, commonly referred to in the trade as shop pans, had been used in shops and factories for carrying in loose or bulk formation from various machines to final inspection machine parts or other articles being manufactured, however such shop pans are objectionable and have proven unsatisfactory. For example, shop pans of the type mentioned are heavy and difficult to handle, especially when loaded. They collect grease and dirt and require frequent cleaning. Moreover, they cannot be stacked satisfactorily and ordinarily provide no means for supporting individually the machine parts or other articles carried thereby. As a result, the machine parts are usually just thrown into the shop pans and frequently are marred or damaged through contact with each other or with the shop pans themselves. Furthermore, the machine parts cannot be cleaned properly in the shop pans during the customary degreasing and washing operations and have to be removed or transferred to other equipment during such operations. Consequently, the machine parts not only require additional handling but also require other means to carry them during or after the cleaning operations mentioned.

In the present instance, the difficulties experienced with shop pans have been overcome by the provision of open baskets, preferably of wire, that are designed so that they contain individual supports for the machine parts.

One of the essential objects of the present invention is to provide a basket structure in which the machine parts or other articles can be carried without being marred during the various stages of manufacture from the initial operation thereon to the final inspection thereof.

Another object is to provide a basket structure that enables the machine parts or other articles carried thereby to remain in loaded position during the degreasing or washing operations.

Another object is to provide a basket structure that is simple in construction, strong and durable, inexpensive to manufacture, and easy to handle and move about.

Other objects, advantages and novel details of construction of this invention will be made more apparent as this description proceeds, especially

2

when considered in connection with the accompanying drawings, wherein:

Figure 1 is a side elevation of a basket embodying my invention;

5 Figure 2 is a fragmentary perspective view thereof;

Figure 3 is a fragmentary longitudinal vertical sectional view through the basket illustrated in Figure 1;

10 Figure 4 is an end view of a basket similar to the basket illustrated in Figure 1 but provided with four runners;

Figure 5 is a fragmentary end view of a slight modification;

15 Figure 6 is a fragmentary longitudinal vertical sectional view through the structure illustrated in Figure 5.

Referring now to the drawings, A is a basket formed entirely of wire and having a substantially rectangular frame 10 of the closed loop type, a pair of laterally spaced, longitudinally extending supporting runners 11 and 12 respectively, transversely extending, substantially U-shaped auxiliary supports 13 at longitudinally spaced points of the frame 10 and runners 11 and 12, article carrying means 14 mounted on the base portions 15 of the auxiliary supports, and transversely extending handles 16 and 17 respectively at opposite ends of the frame 10.

As shown, the frame 10 and auxiliary supports 13 of the basket are formed of medium gauge wire, while the runners 11 and 12 and handles 16 and 17 are formed of heavier gauge wire, and the article carrying means 14 is formed of lighter gauge wire, however any suitable gauge wire or its mechanical equivalent may be employed, as desired.

The frame 10 is at the upper ends of and is rigidly secured to the uprights 18 of the U-shaped supports 13. The bases 15 of these supports rest upon and are rigidly secured to the laterally spaced runners 11 and 12. Preferably the runners 11 and 12 extend the full length of the frame 10 and are provided at opposite ends thereof with upstanding extensions 19 and 20 respectively that are rigidly secured to opposite ends of the frame and terminate above the latter in the handles 16 and 17.

The article carrying means 14 may vary in construction and design, as desired. In the basket A, the article carrying means 14 consists of longitudinally spaced, transversely extending rows of inverted U-shaped members 23 upon which tubular machine parts or other tubular articles (not shown) may be individually sleeved in

upright position. Preferably the U-shaped members 23 extend downwardly between and are rigidly secured to spaced cross rods 24 and 25 respectively that rest upon and are rigidly secured to laterally spaced, longitudinally extending rods 26 mounted on and rigidly secured to the bases 15 of the supports 13.

Thus, from the foregoing, it will be apparent that the article carrying means 14 are supported by the U-shaped members 13 which in turn are suspended from the frame 10 and rest upon and are secured to the runners 11 and 12.

If desired, more than two runners such as 11 and 12 may be provided for the basket to obtain a better distribution of the load. For example, the basket A may be provided adjacent opposite sides thereof with auxiliary runners 40 and 41, as illustrated in Figure 4, but the upward extensions 42 and 43 thereof terminate at and are secured to the frame 10. Only the extensions 19 and 20 of the two runners 11 and 12 adjacent the center of the basket extend above the frame 10 thereof and terminate in handles such as 16 and 17 respectively.

In Figures 5 and 6 I have illustrated a slight modification wherein the basket has upper and lower frames 50 and 51 respectively of the closed loop type connected together by U-shaped supports 52 that rest upon and are rigid with four runners 53 to 56 inclusive. As shown, the bases 57 of the U-shaped supports are on the underside of and are rigid with the lower frame 51 and upon the upper side are rigid with the runners 53 to 56 inclusive, while the upright portions 58 of said supports are suspended from and are rigid with the outer sides of the upper frame 50. The runners 53 to 56 inclusive project beyond opposite ends of the lower frame 51 and have upright extensions 59 to 62 inclusive spaced outward from and free of the ends 63 of the lower frame but in contact and rigid with the outer sides of opposite ends 64 of the upper frame 50. The two outer extensions 59 and 62 respectively at opposite ends of the basket terminate at the upper frame 50, but the two intermediate extensions 60 and 61 respectively at opposite ends of the basket have outwardly opening substantially V-shaped portions 70 that project upwardly above the upper frame 50 and terminate in transversely extending handles 71. Moreover, this construction makes it possible to use satisfactorily a removable or fixed expanded metal tray 80 in the basket for carrying articles of various kinds. Preferably such tray 80 rests upon the lower frame 51 but terminates below the upper frame 50 of the basket and is preferably partitioned for supporting individually the articles to be

carried. The partitions (not shown) of the tray may also be expanded metal and may be rigidly secured together and to the upright sides and ends of the tray, so that a very rigid and strong structure will be provided.

What I claim as my invention is:

1. In a basket structure, a rack forming an open mesh bottom comprising a frame, a series of spaced pairs of spaced metal bars extending across said frame and secured thereto, and a series of spaced upwardly extending metal rods each having one end arranged between the spaced bars of each pair and rigidly connected at said end to each of said bars on opposite sides of each member.

2. In a basket structure, a frame including a closed loop portion, a plurality of U-shaped members connected at their upper ends to opposite sides of said closed loop and depending therefrom, a second closed loop member bent into U-shaped form with the bottom portions of the U extending beneath the aforesaid U-shaped members and secured thereto and the end portions extending upward adjacent to the two other opposite sides of said first mentioned closed loop and being secured thereto and extending thereabove to form handles, a rack forming an open mesh bottom for said basket comprising a series of spaced pairs of spaced bars, means for spacing said pairs and for supporting them on said first mentioned U-shaped members, and a series of upwardly extending spaced members arranged between the bars of each pair, said members being rigidly secured on the opposite sides thereof to each of said bars.

JERRY GERALDS.
